CLAIM

The ornamental design for a heel cushion, as shown.

DESCRIPTION

FIG. 1 is a perspective view of a heel cushion showing my new design;

FIG. 2 is a right side elevational view thereof;

FIG. 3 is a top plan view thereof; and

FIG. 4 is a rear elevational view thereof; and

FIG. 5 is a bottom plan view thereof.

In the various figures of the drawing, the various stippling and hatching is intended as surface shading only and does not connote color.

FIG. 1

FIG. 2

FIG. 3

FIG. 4

FIG. 5
